CLAIM

The ornamental design for a portable monitor, as shown and described.

DESCRIPTION

FIG. 1 is a front, right, and top perspective view of a portable monitor, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of the portable monitor shown within the encircled portion labeled 9 in FIG. 1; and, FIG. 10 is an enlarged view of the portable monitor shown within the encircled portion labeled 10 in FIG. 2.

The evenly-dashed broken lines shown in the drawings are included for the purpose of illustrating portions of the portable monitor that form no part of the claimed design. The dash-dot broken lines encircling portions illustrated in enlargements and illustrated in enlarged views in FIGS. 9 and 10 form no part of the claimed design.
